Primary Examiner — Kevin K Rudzinski*Assistant Examiner* — James P McKane(74) Attorney, Agent, or Firm — Eric Hanscom(57) CLAIM

The ornamental design for a reversible sun hat as shown and described.

DESCRIPTION

FIG. 1 is a perspective view of a reversible sun hat showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a perspective view with the hat brim in the reversed position;

FIG. 9 is a perspective view with the hat brim in an intermediate position; and,

FIG. 10 is a perspective view with the hat brim in a front position.

The evenly dashed broken lines along the surfaces of the reversible sun hat depict claimed stitching.

1 Claim, 10 Drawing Sheets(56)
